UNITED STATES PATENT OFFICE

2,137,481

SWITCH ASSEMBLAGE

William C. Furnas, West Allis, and Sigurd R. Thompson, Milwaukee, Wis.; said Thompson assignor to said Furnas, doing business under the name and style of Furnas Electric Company

Original application July 12, 1937, Serial No. 153,152, now Patent No. 2,108,883, dated February 22, 1938. Divided and this application December 1, 1937, Serial No. 177,588

8 Claims. (Cl. 200—166)

The present invention relates in general to improvements in the art of manufacturing electrical control mechanisms, and relates more specifically to improvements in the construction and operation of switch assemblages and to the stationary contact mountings for such assemblages.

Generally defined, an object of our invention is to provide an improved stationary contact mounting for switch assemblages, which is simple and compact in construction, and which is also highly efficient and well protected when in use.

A more specific object of our invention is the provision of an improved support for the normally fixed contacts of a switch assemblage, and a new mode of mounting such supports in the frame structure of the switch.

An additional specific object of our invention is to provide a new and useful controller for electrical apparatus, which may be manufactured and sold at moderate cost and which is extremely durable and presents a neat appearance.

The above and other specific objects of our invention will be apparent from the following detailed description, and this application is a division of our co-pending application Serial Number 153,152, filed July 12, 1937, which has matured to Patent No. 2,108,883, dated February 22, 1938.

A clear conception of embodiments of the features constituting the present improvement, and of the mode of constructing and of operating switch assemblages built in accordance with our invention, may be had by referring to the drawing accompanying and forming a part of this specification wherein like reference characters designate the same or similar parts in the various views.

Fig. 1 is a central longitudinal vertical section through one of our improved switch assemblages with the closure cover in place and showing the switch in normal open position;

Fig. 2 is a partially dismantled end view of the switch assemblage, showing the enclosing cover released and partially removed from the switch frame;

Fig. 3 is a fragmentary longitudinal horizontal section through the switch assemblage showing one of the fixed contact supports in the act of initial assembly thereof;

Fig. 4 is a similar sectional view showing a subsequent step in the assembly of the fixed contact support; and

Fig. 5 is a complete longitudinal horizontal section through the switch assemblage taken

along the line 5—5 of Fig. 1, and showing the fixed contact supports fully assembled.

While our invention has been shown herein as having been embodied in a particular type of switch mechanism especially adapted to control automobile lifts, it is not our intent to thereby unnecessarily restrict the scope; and while certain sections have been referred to as having been taken along vertical and horizontal lines, it will be obvious that the switch assemblage may be disposed in any desired position other than as shown.

Referring to the drawing, the improved switch assemblage comprises in general a frame having a base composed of upper and lower base plates 9, 10 respectively, the upper of which is provided with integral upwardly projecting end walls 11, 12, and the lower of which has integral upwardly extending side flanges 13 spaced from the opposite side edges of the end walls; a pair of laterally spaced fixed contact bars or supports 14, 15 mounted in the end walls 11, 12 and carrying the fixed contacts 16; an oscillatory movable contact carrying spindle 17 journaled in the end walls 11, 12 between the fixed contacts 16 and providing a support for a series of movable contacts 18, 19 which are cooperable with the fixed contacts 16; and a removable U-shaped cover 20 formed for cooperation with the end walls 11, 12 and with the flanges 13 to completely enclose the switch mechanism.

The upper base plate 9 and the end walls 11, 12 may be formed of a single piece of sheet metal, and the walls 11, 12 may be retained in substantially parallel position by means of a top bar 21 rigidly connecting the upper ends thereof. The upper and lower base plates 9, 10 may be firmly united by spot welding or otherwise; and the end walls 11, 12 are provided with aligned rectangular slots or openings 22, 23 respectively, all of which are of the same height, but of which the openings 22 are somewhat wider than the openings 23. The end wall 11 is also provided with openings 24 for the electrical conductors and with a journal opening for the reduced end of the spindle 17; and both of the end walls 11, 12 are reinforced by outer plates 25 attached thereto by bolts or screws 26. The spindle 17 is directly journaled in the end walls 11, 12 and plates 25, and these plates are somewhat larger than the end walls 11, 12.

The lower contact bars or supports 14, 15 are formed of insulating material and are adapted to be mounted in the end walls 11, 12 of the main frame in the manner shown in Figs. 3, 4 and 5.

Each of these bars or supports 14, 15 may have uniform rectangular cross-sectional area substantially equal to that of the openings 23 in the end wall 12 but of slightly less width than the openings 22 in the opposite end wall 11. The contacts 16 are suspended from the bar supports 14, 15 by resilient conductor arms 27 secured in place by terminal bolts 28 some of which may be joined by a conductor plate 29, and to which the electrical conductors may be attached by means of nuts 30. After the fixed contacts have been attached to the supports 14, 15, the latter may be assembled in the frame walls 11, 12 by first inserting one end of each support 14, 15 through one of the larger openings 22 and by pushing or sliding the support through this opening sufficiently to permit swinging thereof into alignment with the corresponding opposite opening 23, as clearly indicated in Fig. 3. The aligned end of the support 14, 15 may then be driven into the adjacent opening 23 as shown in Fig. 4, until it engages the outer plate 25, whereupon the opposite end of the bar will be flush with the outer surface of the end wall 11. After both of the contact supports 14, 15 have been thus positioned in the openings 23, a U-shaped retainer plate 31 may be applied to the end wall 11 and within the openings 22 in the manner illustrated in Fig. 5, so as to finally lock the adjacent ends of both supports 14, 15 within the openings 22; and the ends of the plate 31 may either be bent into contact with the wall 11 as shown or they may be left in engagement with the outer sides of the supports 14, 15. When thus finally assembled, the supports 14, 15 will be disposed substantially parallel to each other and will be rigidly confined within the openings 22, 23 of both end walls 11, 12, and the reenforcing and sealing plate 25 may be finally applied to the end wall 11 as shown.

When the improved switch assemblage has been properly constructed as above described and connected into the electrical circuit, the movable contacts 18, 19 may be readily swung into engagement with the corresponding normally fixed contacts 16, by merely swinging the operating handle shown in Figs. 1 and 2, so as to rotate the spindle 17. During such movement of the handle the coil spring at the handle end of the spindle, will be placed under tension so that upon release of the actuating handle, this spring will quickly return to normal position and will disengage the contacts 18, 19 from the fixed contacts 16. During oscillation of the movable contacts 18, 19 into position between the fixed contacts 16, the resilient arms 27 will spread apart and will thereby insure tight closing of the switch.

By virtue of the fact that the major portions of the assemblage are all adapted to be formed of sheet metal with the aid of punches and dies, the assemblage may obviously be constructed and sold at moderate cost. The improved method of inserting the fixed contact supports 14, 15 in the manner shown in Figs. 3, 4 and 5, obviously facilitates assembly and produces a durable final structure wherein the fixed contacts are firmly supported. The single retainer plate 31 finally confines both of the supports 14, 15 in proper position relative to the end walls 11, 12, and this plate 31 may obviously be quickly applied, or removed if necessary. The end plates 25 obviously serve to finally confine the supports 14, 15 and the plate 31, and to prevent ingress of moisture through the openings 22, 23. The improved assemblage has proven highly successful in actual commercial use, and besides being readily manip-

urable and readily accessible for inspection, this assemblage may be manufactured at minimum cost and is extremely durable in construction.

It should be understood that it is not desired to limit this invention to the exact details of construction or to the precise mode of operation herein shown and described, for various modifications within the scope of the claims may occur to persons skilled in the art.

We claim:—

1. In combination, a frame having end walls provided with openings, a contact support having one end snugly fitted within the opening in one of said walls and initially loosely fitted within the corresponding opening in the other of said walls, a retainer for snugly retaining the loosely fitted end of said support within its confining opening, and an outer plate coacting with said other wall and providing a seal for the opening with which said retainer coacts.

2. In combination, a frame having spaced end walls provided with sets of aligned openings, a contact support cooperable with each of said sets, each support having one end snugly fitting one opening of the corresponding set and having its opposite end initially loosely confined within the other opening of said set, common means for finally snugly confining all of the loosely confined support ends within the adjacent openings, and a single outer plate coacting with the adjacent wall to seal all of the openings with which said common confining means coacts.

3. In combination, a frame having spaced end walls provided with sets of aligned openings, a contact support cooperable with each of said sets, each support having one end snugly fitting one opening of the corresponding set and having its opposite end initially loosely confined within the other opening of said set, a common U-shaped retainer plate coacting with said walls and with said loosely confined support ends to positively prevent movement of the latter relative to said frame, and a single outer plate detachably secured to the adjacent wall to seal all of the openings with which said retainer plate coacts.

4. In combination, a frame having end walls provided with openings, a contact support having one end snugly fitted within the opening in one of said walls and initially loosely fitted within the corresponding opening in the other of said walls, a retainer for snugly retaining the loosely fitted end of said support within its confining opening, and confining plates coacting with said walls and with the outer portions of said supports and said retainer to seal the adjacent openings.

5. In combination, a frame having spaced end walls provided with sets of aligned openings, a contact support cooperable with each of said sets, each support having one end snugly fitting one opening of the corresponding set and having its opposite end initially loosely confined within the other opening of said set, common means for finally snugly confining all of the loosely confined support ends within the adjacent openings, and an outer plate coacting with said common means and with the adjacent end wall.

6. In combination, a frame having spaced end walls provided with sets of aligned openings, a contact support cooperable with each of said sets, each support having one end snugly fitting one opening of the corresponding set and having its opposite end initially loosely confined within the other opening of said set, a common U-shaped retainer plate coacting with said walls and with

said loosely confined support ends to positively prevent movement of the latter relative to said frame, and outer plates coacting with said walls for sealing said openings and for confining said 5 U-shaped retainer plate.

7. In combination, a frame having spaced end walls provided with sets of aligned openings, a contact support cooperable with each of said sets, each support having one end snugly fitting 10 one opening of the corresponding set and having its opposite end initially loosely confined within the other opening of said set, a retainer plate coacting with all of said supports to prevent movement thereof relative to said frame, and 15 outer confining plates for said retainer plate and for said supports coacting with said end walls.

8. In combination, a frame having spaced integrally united end walls provided with aligned socket openings, a contact support having opposite polygonal ends of approximately the same cross-sectional area, one of said ends snugly slidably fitting the socket formed by one of said openings and the other of said ends loosely initially fitting the other of said openings, a retainer for snugly confining said loosely fitted end within the adjacent enlarged opening, and 10 detachable means secured to the adjacent wall for completely sealing said enlarged opening and for holding said retainer in place. 5
